LADY'S STOCKING

Cyril William Livingston, New York, N. Y., assignor to Sanson Hosiery Mills, Inc., Philadelphia, Pa., a corporation of Delaware

Application September 4, 1951, Serial No. 16,494

Term of patent 14 years

(Cl. D47—7)

To all whom it may concern:

Be it known that I, Cyril William Livingston, a citizen of the United States of America, residing at Manhattan, in the county of New York and State of New York, have invented a new, original, and ornamental Design for a Lady's Stocking, of which the following is a specification, reference being had to the accompanying drawing, forming a part thereof.

The drawing is a rear view in perspective of a lady's stocking showing my new design, with portions thereof lined for shading purposes only.

The characteristic feature of my design resides in the combination on the back of a lady's stocking of a bow-knot representation in or above the high splice substantially as shown.

I claim:

The ornamental design for a lady's stocking, as shown and described.

CYRIL WILLIAM LIVINGSTON.
